UNITED STATES PATENT OFFICE.

JAMES W. BRYCE, OF BLOOMFIELD, NEW JERSEY.

CLOCK-WINDING MECHANISM.

1,299,116.

Specification of Letters Patent.

Patented Apr. 1, 1919.

Application filed July 31, 1917. Serial No. 183,668.

To all whom it may concern:

Be it known that I, JAMES W. BRYCE, a citizen of the United States, residing at Bloomfield, in the county of Essex and State 5 of New Jersey, have invented certain new and useful Improvements in Clock-Winding Mechanism, of which the following is a full, clear, and exact description.

This invention relates to certain new and 0 useful improvements in clock winding mechanism and has for its object the provision of devices which will automatically restore energy in a clock driving motor such as a spring. The power for winding the spring 15 is preferably derived from an electric power circuit, for example an electric light circuit. Electric lighting circuits have been previously used for rewinding clock springs, but in many cases this method of applying the 20 energy of an electric light circuit for clock winding purposes has been unsatisfactory since the current in the lighting circuit was subject to interruptions and in case the clock motor ran down at a period when the current 25 was off the line, no rewinding would occur and the clock would stop.

On account of the fact that the current 30 interruptions in these electrical power circuits do not take place at any stated intervals or stated times, difficulty has been encountered with many electrical rewinding clocks. Certain of these clocks rewind at certain different time intervals, for example 35 every minute or every hour. If the current was interrupted during these particular time instances, the rewinding would not take place 40 properly. In factories there is usually a complete current interruption from a certain time on Saturday until Monday morning, and sometimes with a holiday on Monday, the current would be interrupted until the 45 succeeding day. The present invention provides a clock spring and motor rewinding device of such character that the clock spring will carry over for these long durations of periods of current interruptions.

In the use of clocks for driving or controlling the drive of workmen's time recorders the rewinding circuit is usually a factory 50 power circuit. On these circuits there is a complete interruption of current during the night and the use of minute rewinding or hour rewind clocks is precluded in such places. With the present invention the con-

struction of the parts is such that should 55 the clock run down to the point at which the motor would start the rewinding action during the night, the switch will be thrown to connect the motor in circuit and the motor will start up and effect rewinding at the 60 time when the current again comes upon the line. The clock spring, however, is of such a character and is so disposed that the 65 clock will be carried over these periods of current interruption without stopping.

Other objects of the invention reside in the provision of a train of mechanism between the winding motor and the clock spring of such character that the winding 70 of the spring by an electric motor does not in any way affect the operation of the clock.

Other objects of the invention reside in the provision of certain details of construction which make the apparatus simple and inexpensive to manufacture and not likely 75 to get out of order when in use. The construction herein explained also employs many well known standard electric parts which have been proven satisfactory in practice in other applications and which are safe 80 from an insulation standpoint.

In the drawings Figure 1 is a front elevation of a clock having associated therewith my improved rewinding mechanism. Certain parts of the clock dial are shown broken 85 away to show the interior construction.

Fig. 2 is a side elevation of the construction shown in Fig. 1 showing the gear connections between the winding motor and the 90 clock spring.

Fig. 3 is an enlarged detail view of a portion of the gear train shown in Fig. 1, and with the front frame plate and certain other parts broken away to show the interior construction. This figure is taken substantially 95 on line 3—3 of Fig. 2.

Fig. 4 is a detail sectional view taken on line 4—4 of Fig. 3.

Fig. 5 is a cross sectional detail view of one of the clock winding springs and a part 100 of the gear train for rewinding the spring. This view is taken on line 5—5 of Fig. 3.

Fig. 6 is a side view of the differential mechanism forming a part of the winding train. This figure shows the right hand side 105 of the differential shown in Fig. 4, with the left hand gear removed.

Fig. 7 is a detail view showing how the

frame plates of the mechanism are supported together, and how the worm shaft is supported in position.

Fig. 8 is a detail view of the electric switch which controls the current to the rewinding motor. This figure also shows the operating connections between the switch and the clock Geneva sector. This Geneva sector is adapted to close the switch after 10 the spring is wound down to a certain predetermined extent.

Figs. 9 and 10 are detail views showing a detachable gear which may be applied to the end of the motor driven worm shaft for 15 winding the clock by hand.

Figs. 11, 12 and 13 are detail views of a modified method of winding the clock spring. These views illustrate a construction in which the spring is wound from one 20 end in which the clock drive is taken off from the other end of the spring.

In more detail in the drawings, 10 is the cabinet containing the clock rewinding mechanism. The clock has the usual minute hand 11 and hour hand 12, interconnected through gears 13 and 14 in the usual manner. The details of the clock mechanism are not shown as they are of usual construction. It is sufficient here to state that gear 15, 25 shown in Fig. 2 is a gear which meshes with the usual clock train. This gear 15 connects with the driving spring through the train of gearing now to be described.

Referring to Figs. 3 and 5, gear 15 has 30 rigidly secured thereto a spur gear 16 (see Fig. 5) which gear meshes with a small pinion 17, which in turn meshes with a similar small pinion 18. These gears 17 and 18 are best shown in Fig. 3. They rotate on studs 40 19, which studs are rigidly secured to two annular rings 20. These annular rings 20 are secured together by three studs 21, and are spaced apart by coöoperating spacing blocks 22. The studs 21 secure the annular 45 rings 20 to a large gear 23 (see Fig. 5). It is this gear 23, which connects with the electric motor rewinding mechanism as will be hereinafter described. Referring again to the two interconnecting small pinions 17 and 50 18, pinion 18 intermeshes with the gear 24, which is preferably pinned to the central spring arbor 25. This spring arbor 25 has fastened rigidly to it the inner end of the coil spring 26. The outer end of this 55 coil spring 26 is rigidly fastened to a post 27, carried by a frame part on the machine and best shown in Fig. 5. From the ensuing description it will be seen that the clock spring 26 both drives the clock mechanism and is rewound at the same end thereof. The differential train of gearing just 60 described causes the spring to exert energy upon the clock mechanism.

First consider the motor winding gear 23 65 stationary, which is the normal condition

when rewinding is not occurring. Spring 26 will turn shaft 25 clockwise thereby turning pinion 24 and through intermeshing pinions 18 and 17, driving gears 16 and 15 in a counterclockwise direction to turn the clock 70 mechanism.

Now consider gear 23 rotating in a counterclockwise direction which is its direction of movement when the motor (to be hereafter described) is rewinding the spring. 75 As gear 16 cannot move ahead faster than the clock will permit it, the pinions 17 and 18 will act as a differential and drive the gear 24 in a counterclockwise direction. This counterclockwise direction of movement of gear 24 will rewind the clock spring 26. Due to the differential connection between gears 16 and 24, while the spring 26 is being rewound by an electric motor which drives gear 23 it will be possible for the 80 clock to continue to move ahead under the influence of the torque of spring 26 and the rewinding torque which is imparted from gear 23.

The foregoing description has been given 90 with reference to the construction shown in Fig. 5 and the part shown in the upper right hand corner of Fig. 3. It will be understood that in the present construction there are two springs and two corresponding 95 trains of gearing for driving them. The description need not be repeated for the second spring as the action is identical. Gears 23 both intermesh with the common gear 28, best shown in Fig. 3. It is through this 100 common gear 28 that the connections to the motor driving mechanism are made.

Motor rewinding mechanism.—Fig. 2, shows an electric motor M of any suitable type which through coupling 30 drives a 105 worm shaft 31. Worm 32 on this shaft turns worm-gear 33 in a counterclockwise direction. This worm gear which is shown in Figs. 1, 2 and 3 is rigidly secured to a hub 34. This hub carries two pinions 35 and 36, one on each end thereof, these pinions being rigidly fastened to the hub and to the worm gear so as to rotate in unison therewith. The left hand pinion 35 meshes with a pinion 37, forming one part of a speed reducing differential mechanism (see Fig. 4). The pinion 36 on the right hand side of hub 34 meshes with an idler gear 38 (see Figs. 2 and 3). This idler gear 38 in turn meshes with a pinion 39, which is also 115 a part of the differential speed reducing gear. The function of the idler pinion 38 is to reverse the direction of movement imparted to gear 39 by 36, so that this gear 39 will move in an opposite direction of rotation to the movement of gear 37. In order that gears 37 and 39 should not move at equal speeds the number of teeth on one side of the train leading to the gear 39 is different from the number of teeth on the 120 125 side leading to gear 37.

other side. This difference in pitch ratio is quite slight so that gear 39 will have a slightly higher speed of rotation counterclockwise than will the speed of clockwise 5 rotation of gear 37. Gear 37 has secured to it a bevel gear 40. Gear 39 has likewise secured to it a bevel gear 41. These bevel gears are free to rotate about a shaft 42 suitably carried in the frame of the machine. 10 Also freely rotatable about the shaft 42 is a cage 43, carrying studs 44 which form journals for bevel pinions 46. These pinions 46 intermesh on their opposite sides with bevel gears 40 and 41 respectively. The parts 15 just described constitute a speed reducing differential, and the motion of the gears is such that the cage 43 of this differential will slowly progress about shaft 42 in a counterclockwise direction. The cage 43 has 20 secured to it at the left, as shown in Fig. 4 and Fig. 2, a spur gear 47. This spur gear 47 intermeshes with gear 28 and is adapted to drive it in a clockwise direction during the revolution of the motor M. The object 25 of the differential mechanism shown in Figs. 4 and 6 is to permit the motor M to make a large number of revolutions during an extremely small number of revolutions of the gear 28, and its interconnected clock springs 30 26. This differential reducing gear construction permits an extremely small motor to be used for rewinding purposes and also rewinds the spring slowly, thereby preventing frequent breakages due to sudden winding 35 shocks being imparted to the springs.

Motor driving mechanism.—In order that the electric circuit to the rewinding electric motor M be established I provide a switching mechanism which is controlled in accordance with the condition of springs 26. 40 It may be here stated that this switching mechanism is so arranged that the circuit will be established to the motor M long before the springs have become entirely unwound. In other words a large amount of energy is at all times in reserve upon the springs whereby the clock can be driven for an extended period without the springs being rewound by the electric motor. By an arrangement now to be described it is possible for the clock spring to "carry over" 45 for long periods irrespective of interruptions of the source of electric power for operating the motor M.

50 On the end of spring shaft 25 is a one tooth gear 50 (see Figs. 5, 1 and 8). This one tooth gear it will be understood rotates as the springs unwind and upon every complete revolution thereof the single tooth is 55 adapted to advance a segment plate 51, one step in a counterclockwise direction. One-tooth gear 50 and segment plate 51 operate on the "Geneva stop" principle which is so well known that its action need not be described in further detail. When the segment

plate 51 has advanced a predetermined number of steps in a counterclockwise direction a pin 52 carried by this plate will contact with an arm 53 of a switch controlling plate 54. This switch controlling plate is pivoted to rock on stud 55 and has a lower depending end 56 engaging between collars on a spindle 57 (see Fig. 8). This spindle 57 on its end carries an element of a canopy switch 58. This canopy switch is the well known type now on the market and need not be described in further detail. It is sufficient to state that when spindle 57 moves to the left under the influence of plate 54, the circuit will be established from wires 59 70 to wires 60 which lead to the motor M. Switch 58 is preferably incased in a metal box 61 and the wires 59 lead into this box through a conduit 62. The upper end of conduit 62 carries a socket 63 through which 75 extend the wires to the electric power circuit (see Fig. 1). Wires 60 extend out of the box 61 through a porcelain insulator 64. These parts it will be understood are standard electrical apparatus and need not be 80 described in further detail except to state that they are adapted to prevent any leakage of current in or about the clock which might cause short circuits and possible 85 danger of fire.

90 Referring again to the segment 51 it should be noted that should the pin 52 contact with fork 53 and rock the plate 54 while the electric motor circuit is broken due to the interruptions in the current supply, pin 52 will pass beyond the fork 53, but plate 54 will remain in its displaced position maintaining the circuit established at switch 58. As the spring 26 is rewound by the electric motor the spring arbor 25 100 will be rotated in a counterclockwise direction. The arbor 25 will turn one tooth gear 50 counterclockwise and the rotations of this gear will advance plate 51 with a step by step movement in a clockwise direction 105 until pin 52 contacts with the arm 65 on plate 54. The pin 52 will then cam arm 65 downward thereby rocking plate 54 counterclockwise, shifting spindle 57 to the right and breaking the electric circuit by means 110 of switch 58. The rotation of the motor M will then cease just before the springs are 115 completely rewound.

In order that the condition of the spring may be at all times apparent I preferably 120 provide an indicating mechanism comprising a pointer 70 connected with a link 71, operated by a plate 51^a. This plate is in all respects similar to the plate 51 heretofore described, and is driven from the 125 spring arbor shaft 25 of the other, namely the right hand spring.

In order to rewind the spring 26, should the motor become disabled, I provide an adjustable winding gear which is shown in 130

Figs. 9 and 10. This winding gear comprises a stub shaft 75 which is adapted to take into a recess 76 in a frame member of the machine. The stub shaft 75 carries a 5 large pinion 77 which has secured on the outer face thereof a handle 78. Pinion 77 is adapted to mesh with the pinion 79 on the end of the worm shaft 31. By means of this winding apparatus the spring can 10 be wound up should the motor M be dis- abled for any reason. Fig. 7 shows the mounting of the worm shaft 31. This worm shaft is journaled in the box 80 which forms 15 spacing members intermediate the two frame members 81. The said frame members are held together by means of the stud 82.

I also contemplate the employment of a phonograph type of spring, in which the 20 spring is wound up at one end and in which the drive to the clock is taken off from the opposite end of the spring. This construction enables me to dispense with the differential gear illustrated in Fig. 5. In Fig. 11, 25 gear 28 which corresponds with a similar lettered gear in Fig. 3, meshes with the spur gear 90. This gear 90 has fastened to it a sleeve member 91 which is notched as shown at 92 (see Fig. 11) to receive rollers 30 93 which coat with an annular hub 94 pinned to an arbor shaft 95. Arbor shaft 95 has fastened to it a spring 96 which spring, at its outer end, is fastened to a cage 97. Cage 97, in turn, has fastened to 35 it a gear 98 which drives the clock mechanism. This gear, it will be understood, corresponds with gear 15 as shown in Fig. 5. It may be here stated that with the construction just described it is necessary that 40 gear 28 be driven in a reverse direction than heretofore. This is preferably accomplished by changing the ratio of the teeth on the speed reducing differential gear illustrated in Fig. 2. In winding spring 96 the 45 gear 90 rotates in a clockwise direction there- by clamping the balls 93 against notches 92 and against the boss 94, and thereby carrying the arbor 95 around in unison with gear 90. During the time of this rewinding 50 it will be readily understood that power can be transmitted to the clock mechanism through gear 98 since this gear 98 is connected to the outer and opposite end of the spring. The purpose of the ball 55 clutch mechanism, shown in Figs. 11 and 12, is to permit the arbor shaft 95 to be rewound by hand by applying a key to the squared end 95a. When the key is thus utilized the balls 93 will be cammed around into the 60 deep part of the notches 92 and the arbor 95 can then be turned without turning gear 90 and its interconnected gear train.

It will be understood that my invention 65 is susceptible of various modifications which will be clear to those skilled in the art.

What I claim as my invention is more particularly pointed out in the appended claims.

I claim:

1. A device of the class described, comprising in combination, a clock driving motor in which power may be stored to drive the clock, means for restoring power therein from time to time, said means comprising an electric motor, and a gear train connecting 70 said electric motor and the clock driving motor, said gear train comprising in part a differential gear having different numbers of teeth thereon at the opposite sides thereof, whereby the electric motor may rotate at a 80 high speed and the clock motor may be re-wound at a comparatively slow speed.

2. A device of the class described, comprising in combination, a clock driving motor in which power may be stored for driv- 85 ing the clock, an electric motor for restoring power therein, and a gear train connecting said electric motor and the clock motor, said gear train comprising in part a differential gear so associated with the clock motor that 90 the latter may continue to exert energy upon the clock mechanism during a restoring of power in said clock motor by the electric motor.

3. A device of the class described, comprising in combination, a clock driving motor such as a coiled spring adapted to have power stored therein, an electric motor for restoring power therein from time to time, a gear train intermediate the electric motor 100 and the clock driving motor, said train including a speed reducing differential gearing adapted to permit the electric motor to rotate at high speed when restoring energy in the clock motor at low speed, and a second 105 differential gearing so associated with the clock motor that the said clock motor will exert energy upon the clock mechanism during the operation of restoring energy therein.

4. In a device of the class described, in combination, a clock mechanism, a spring for driving said mechanism, an electric motor for rewinding the said spring, an electric circuit, a switch for connecting the motor to the electric circuit, a rocking plate for actuating said switch, and means actuated in one direction by the clock spring as it acts upon the clock mechanism to shift and set said rocking plate to close the electric circuit at 115 a predetermined time, and actuated in the reverse direction by said spring when the latter is being rewound and acting upon said rocking plate at a predetermined time to shift and set the same to open said switch. 120

5. In a device of the class described, in combination, a clock mechanism, a spring for driving said mechanism, an electric motor for rewinding the said spring, an electric circuit, a switch for connecting the motor 125 130

to the electric circuit, a rocking plate for actuating said switch, a Geneva stop plate adapted to be actuated in one direction by the clock spring as it acts upon the clock mechanism, whereby to shift and set said rocking plate to close the electric circuit at a predetermined time, said Geneva stop plate being actuated in the opposite direction by the clock spring when said spring is being rewound and acting upon said rocking plate at a predetermined time to shift and set the same to open said switch.

6. In a device of the class described, in combination, a clock mechanism, a coiled spring for driving the said mechanism, an electric motor for rewinding the said coil spring, a power circuit, a switch for connecting the motor to the power circuit, means for actuating said switch, said means comprising a member adapted to be shifted in one direction to close the switch and to be shifted in an opposite direction to open said switch, and a Geneva stop plate adapted to be positioned by a part moved in accordance with the degree of winding of the spring for actuating the aforesaid member.

7. In a device of the class described, in

combination, a clock mechanism, a plurality of springs for driving the same, and means for rewinding said springs, said means comprising an electric motor, a worm shaft driven thereby, a worm gear driven by said worm, a speed reducing differential gear driven by said worm gear, a main driving gear driven by the cage of the aforesaid differential gear, and connections between said main driving gear and said springs for rewinding the same.

8. In a device of the class described, in combination, a clock mechanism, a plurality of springs for driving the same, and means for rewinding said springs, said means comprising an electric motor, a worm shaft driven thereby, a worm gear driven by said worm, a speed reducing differential gear driven by said worm gear, a main driving gear driven by the cage of the aforesaid differential gear and so associated with said spring as to cause the energy of the springs to be continuously exerted upon the clock mechanism during the rewinding operation.

In testimony whereof I hereunto affix my signature.

JAMES W. BRYCE.
